UNITED STATES PATENT OFFICE.

WILLIAM H. FAUBER, OF NEW YORK, N. Y.

ENGINE-VALVE.

1,127,980.

Specification of Letters Patent. Patented Feb. 9, 1915.

Application filed July 21, 1913. Serial No. 780,096.

To all whom it may concern:

Be it known that I, WILLIAM H. FAUBER, a citizen of the United States, and a resident of New York, in the county of New York and State of New York, have invented certain new and useful Improvements in Engine-Valves; and I do hereby declare that the following is a full, clear, and exact description thereof, reference being had to the accompanying drawings, and to the letters of reference marked thereon, which form a part of this specification.

This invention relates to valves for controlling the admission or exhaust of fluid to or from a space or chamber subject to fluid pressure, such as the cylinder of an engine, pump, compressor, or the like.

My invention includes features of construction applicable to valves of that kind embracing a valve casing having a cylindric valve chamber and a cylindric valve member having bearing in said valve chamber, and it also includes features of construction applicable to valves of that kind described in my prior application, Serial Number 735,839, filed December 9th, 1912, wherein the pressure tending to lift the movable valve member from its seat is resisted or counteracted by a movable pressure block, in connection with means operated by the pressure within the cylinder and acting upon said pressure block to press the same against said valve member and the latter toward its seat.

The objects of my invention are to provide improved features of construction in valves of the kind stated, in a number of particulars, as will hereinafter appear.

The several features constituting my invention are illustrated in the accompanying drawings, as applied to a single cylinder, internal combustion engine, but it is to be understood that the principal features of the invention may be applied to internal combustion engines having a plurality of cylinders, and that some of the features of the invention may be applied to rotary as well as reciprocating engines and to pumps or compressors, as well as to engines.

The invention consists in the matters hereinafter described and pointed out in the appended claims.

In the accompanying drawings—Figure 1 is a sectional view of a valve embodying some of the principal features of my invention, taken on line 1—1 of Fig. 2; Fig. 2 is

a plan view of the valve with parts broken away to show a portion of the valve seat; Fig. 3 is a view in central longitudinal section of the valve shown in Figs. 1 and 2; Fig. 4 is a view in end elevation of the form of valve shown in Figs. 1 to 3; Fig. 5 is a detail section, taken on line 5—5 of Fig. 2; Fig. 6 is a detail section, taken on line 6—6 of Fig. 2; Fig. 7 is a detail section, taken on line 7—7 of Fig. 2; Fig. 8 is a cross-section corresponding to Fig. 1, showing a form of valve containing additional improvements; Fig. 9 is a longitudinal section, taken on line 9—9 of Fig. 8; Fig. 10 is a detail plan view of the parts shown in Fig. 8, with the valve and pressure block removed from the valve casing; Fig. 11 is a sectional view taken on line 11—11 of Fig. 12, the same corresponding with Figs. 1 and 8 and showing a modification of the construction shown in said Fig. 8; and Fig. 12 is a plan view of the form of valve shown in Fig. 11.

In the accompanying drawings, I have illustrated my invention in connection with the power cylinder 5 of an internal combustion or explosive engine. Said cylinder 5 is provided with a valve casing 6 made integral with the head of the cylinder and provided with a cylindric valve chamber which extends transversely with regard to the central axis of the cylinder and within which is located a rotative cylindric valve member 7.

At one side of the valve casing 6 is an admission pipe 9 forming a passage through which the explosive mixture is delivered to the valve and which is provided with an admission opening 9^a. At the opposite side of the valve casing, an exhaust pipe 10 is provided, said pipe being provided with an exhaust opening 10^a.

The valve chamber is provided with a cylinder port 11 which extends lengthwise of the valve casing and transversely of the cylinder head and opens from the valve seat through the cylinder head into the interior of the cylinder. The valve chamber is also provided, at one side of the cylinder port, with two admission ports 12, 12^a and at the opposite side of the same with two exhaust ports 13, 13^a. The ports 12, 12^a are arranged in line with each other longitudinally of the valve casing, as are also the exhaust ports 13, 13^a. The ports 12, 12^a, in one instance, and the ports 13, 13^a, in the other instance, are separated from each

other by bridge members 14, 15 (Fig. 8), forming part of the cylinder head and arranged in line with each other circumferentially of the valve chamber. The supply ports 12, 12^a are connected with the supply pipe 9, while the exhaust ports 13, 13^a are similarly connected with the exhaust pipe 10.

The cylindric valve member 7 is provided with two laterally facing recesses 16, 16^a arranged at opposite sides of the valve member or at an angular distance of 180° apart and corresponding in length with the cylinder port. Said admission and exhaust ports are located at angular distances from the cylinder port corresponding with the width of the valve recesses 16 and at approximately an angle of 45° with regard to said cylinder port. The valve, as illustrated, is designed for a four-cycle, internal combustion engine and the valve member 7, having two valve recesses 16, 16^a at opposite sides thereof, is turned or driven, by suitable connection with the crank shaft of the engine, in such manner that the valve member will be rotated once for each four revolutions of the crank shaft, so that its speed of rotation will be one-half that of a valve member provided with only one valve recess, such as illustrated in my prior application, Serial No. 358,839, hereinbefore referred to. The said recesses 16 and 16^a are adapted in the rotative movement of the valve member to bring the cylinder port alternately into communication with the two inlet ports and the two exhaust ports, and a complete cycle of operation of the engine will take place once in each complete rotation of the valve member.

In the top wall of the valve casing between the inlet and exhaust ports is formed a longitudinally extending slot or opening preferably made somewhat wider than the diameter of the valve member 7 and equal in length to the same. Within said opening is located a movable pressure block 18. Said block 18 has a concave inner face which bears against the cylindric surface of the valve member 7 at the side of the same diametrically opposite the part of the valve seat containing the cylinder port. Said pressure block is pressed or held against the valve member by means as follows: An auxiliary cylinder 19 is provided on the cylinder head, the same communicating at one end with the interior of the cylinder. A piston 21 is located in said cylinder and has attached thereto a piston rod 22 arranged to act on a lever 23 located above and pivotally connected with the valve casing. As shown, the cylinder 19 opens at its upper or outer end into the inlet passage 9, and the piston rod passes through a removable cap 9^b in the top wall of said inlet passage. Said lever 23 is adapted to act upon one side

of said pressure block 18 while the opposite side of said pressure block is held from outward movement by means of a plate 24 attached to the valve casing and overlapping an outwardly facing shoulder 25 on the pressure block. At the exhaust side of the valve, the pressure block is spaced slightly from the valve casing and is held by the plate 24 at its lower edge closely against an upwardly facing surface or shoulder on said valve casing, while at the inlet side of the valve, a space is provided between the pressure block and the valve casing to provide for expansion, wear and movability of the block. A packing strip or gasket 18^a is inserted in a groove in the side wall of the casing, and bears against the pressure block to close the said space. By reason of these features, the pressure block has slight freedom of motion in a sidewise direction, so that it may adjust itself perfectly to the surface of the valve member. Moreover, said pressure block, at the exhaust side of the valve, is held closely against the shoulder on the casing, so that oil cannot escape and dust cannot enter at this point.

In the construction shown, the lever 23 is provided with an elongated bearing member 23^a, which extends longitudinally of the pressure block and has bearing at its ends in bearing blocks 26, 26, which are secured by screws 26^a, 26^b to the valve casing. The bearing member 23^a is provided with arms 23^b, 23^c which are adapted to bear downwardly against an upwardly facing shoulder 25^a formed on the adjacent side face of the pressure block.

The lever 23, which is shown as extending outwardly beyond the piston rod 22, is provided with a finger piece 23^c, to which the hand may be applied for depressing the outer end of said lever to relieve the pressure block from the action of said lever when it is desired to remove the pressure block endwise from the valve casing.

Interposed between the piston rod 22 and the valve casing, is a spring 27 arranged to act constantly on said piston rod, to move the same endwise toward the lever 23, or in the same direction in which it is moved by the pressure within the cylinder acting on the piston 21. As shown, the spring 27 is in the form of a tapered, coiled spring which bears at its base against an annular seat, formed on the casing, around the upper end of the cylinder 19, and at its upper end against a collar 22^a on said piston rod. The spring 27 thus arranged acts to exert constant pressure of the piston rod against the lever 23 and through said lever against the pressure block, to hold said pressure block in contact with the valve member 7. Said spring is made to act with a sufficient pressure to hold the pressure block in contact with the valve 7 and the latter in contact

with its seat, at times when there is a partial vacuum in the cylinder tending to draw the piston 21 downwardly or inwardly, thereby preventing the pressure block from being lifted and the valve member rising from its seat under vertical movement or jarring of the engine such as takes place in an automobile or motor-cycle. The said spring also serves to take up all lost motion in the parts 10 between the piston rod and the valve member.

Now referring more particularly to the details of construction shown in Figs. 1 to 7 inclusive of the accompanying drawings: the pressure block 18 is recessed in its upper portion and is provided with a plurality of crosswise, vertical partitions, to give rigidity thereto. The recessed top of the block is closed by means of a separate cover plate 18^b engaged at its side edges with longitudinal grooves in the vertical side portions of the pressure block. Said pressure block, at one end of the same (Figs. 2 and 5), is provided with longitudinal and transverse partitions, forming with the cover plate a space or chamber 28 which communicates with the interior of the valve chamber by means of a port 28^a. The wall of the said pressure block adjacent to said chamber 28 is provided with a plurality of air inlet openings 29. This construction provides means by which air may be admitted to one end of each of the valve recesses 16, 16^a, when either of said recesses is in position 35 for communication with said port 28^a, as shown in Fig. 5. At its end opposite that containing the chamber 28, the pressure block is provided with partitions forming a chamber 30, which communicates, by means 40 of a port 30^a, with the interior of the valve chamber; said port 30^a being arranged in longitudinal alinement with the port 28^a. Said chamber 30 extends through the end 45 of the pressure block and communicates with a space or chamber 31 formed on the end of the valve casing exterior to the valve member, by means of a recessed cap plate 32. Said cap plate is shown as held in place by two screws 32^a, 32^b (Fig. 4) inserted into 50 the end of the valve casing. For the end-wise removal of the pressure block from the valve casing, the screw 32^a can be removed and the cap plate swung on the screw 32^b to a position to permit such removal. 55 Said space or chamber 31 is in communication with a laterally arranged outlet pipe 31^a (Fig. 2) which leads to and is connected with the air inlet to the carbureting device of the engine. The purpose of the chambers 28 and 30, arranged and connected as 60 described, is to secure the removal from the valve recesses 16, 16^a of all of the gas or explosive charge received by said valve recesses from the inlet ports 12, 12^a and carried from said inlet ports toward the ex-

haust port and to replace the gas with air. The outlet pipe 31^a being connected with a pipe or space subject to a vacuum, and the chamber 28 being in communication with the open air, it follows that, when the opposite ends of one of the valve recesses 16, 16^a are brought into communication with the chambers 28 and 30, an inward flow of air will be induced through the chamber 28 into one end of the valve recess, while any portion of the charge, or gas, contained in said recess will be drawn from the opposite end of said recess through the chamber 31 and the outlet pipe 31^a. Perhaps this will be better understood by making specific reference to Fig. 1 of the drawings. In this figure, the valve member 7 is shown in the position it occupies when the valve recess 16 provides communication between the inlet ports 12, 12^a and the cylinder port 11, while the opposite valve recess 16^a is in communication at its ends with the ports 28^a and 30^a, respectively. With the engine piston in the cylinder 5 on its downward or suction stroke, a partial vacuum is created in the air inlet 75 of the carbureter, which accomplishes the two-fold function of supplying an explosive mixture to the engine cylinder and creating a partial vacuum in the valve recess 16^a through the port 30^a and pipe 31^a. Air is thus drawn into the valve recess 16^a through the port 28^a and any portion of the charge of gas in said valve recess 16^a will be drawn into the carbureter through the pipe 31^a. In this manner the valve recess 16^a is cleared 80 of any portion of the charge of gas that may be contained therein by scavenging air entering said valve recess through the port 28^a. 85 As an improved construction in the exhaust pipe 10, in Figs. 1 to 4, I have shown the same as consisting of a single piece of sheet metal, separate from the valve casing. Such separate pipe is made of cylindric form, with an integral, lateral, transverse neck forming the outlet 10^a. The pipe 10 thus made is adapted to fit within a concave, laterally facing seat, formed on the side wall of the valve casing at the exhaust side of the same. Between the said pipe and the seat therefor on the valve casing, is located a 90 heat-insulating layer 10^b (Fig. 1). The said pipe is provided with a plurality of lugs 10^c, 10^d (Fig. 2), through which are inserted screws or bolts 10^e, 10^f, which enter the side wall of the valve casing and serve to hold 95 said pipe in place on the said casing. By making the said exhaust pipe 10 separate from the valve casing, and providing the interposed insulating layer 10^b, adapted to prevent the transmission of heat from said 100 pipe to the valve casing, the said pipe may expand and contract without producing any corresponding expansion and contraction in the valve casing at the exhaust side of the same, thereby avoiding liability of distortion. 105

tion of the valve casing through unequal expansion and contraction of the same at its inlet and exhaust sides.

Any suitable means may be employed for driving or giving rotative movement to the valve member to accord with the rotative movement of the crank shaft of the engine, the features shown in the drawings for this purpose (Figs. 1 and 3) being made as follows: A shaft 33 extends through the interior of the valve member and at one end is connected with said valve member. The means of connection shown consists of a pin 34 which is secured at its ends in the end portion of the valve member and passes loosely through a transverse aperture in the adjacent end of said shaft 33. To the opposite end of said shaft 33 is secured a sprocket-wheel 34^a, over which is trained a driving chain or belt 35 which receives its motion from the crank shaft of the engine. An anti-friction bearing is provided between the end of the shaft 33 adjacent to the sprocket-wheel 34 and the part 6^a of the valve casing which surrounds said shaft beyond the adjacent end of the valve chamber. As illustrated, a bearing sleeve 33^a is mounted on the cylindric end portion of the shaft 33 and a series of bearing balls 35^a are interposed between a groove 33^b in said sleeve and an annular fixed bearing, formed by means of two bearing rings 36 which are secured in an annular seat on the part 6^a of the valve casing. The bearing groove 33^b is made considerably wider than the bearing balls 35^a so that the valve member 7 may have a slight degree of endwise movement or play to prevent the wearing of grooves in the valve member and valve seat. The sprocket-wheel 34^a is shown as secured directly to the bearing sleeve 33^a while said bearing sleeve is held from turning or rotation on the shaft 33 by means which permit said sleeve to turn without driving the valve member in case the valve member should be held from rotation by the introduction of some hard object into the valve, or otherwise. As illustrated, the shaft 33 is provided with a transverse bore 33^c in which is located a ball 36^b and a coiled spring 36^a, which latter acts on said ball in a direction to force the same beyond the end of the said bore. The bearing sleeve 33^a is provided with a recess adapted to receive the portion of said ball 36^b which is thrust outwardly beyond the end of said bore by the action of the spring 36^a. The engagement of the ball 36 with the said recess serves to afford a driving connection between the sprocket-wheel and the shaft, which will prevent any relative rotation of these parts under usual conditions of operation, but will permit the backward yielding of the shaft and valve member when required to prevent breakage of the parts.

The general operation of the means for maintaining pressure of the pressure block against the valve member, embracing the piston 21 and means for transmitting pressure from said piston to the pressure block, is like that set forth in my prior application hereinbefore referred to, the pressure transmitted from the piston to the pressure block being variable in accordance with the increase and decrease of pressure within the cylinder. In this connection, it is to be understood that the movement given to the pressure block is very slight, and is due to the action of the lever 23 on one side of said pressure block; the other side of said block being held from rising by the fixed plate 24. The construction in which the pressure block is engaged at one side with the valve casing and at its opposite side with the lever 23, has the advantage that when the outer end of the lever 23 is depressed to relieve the pressure of said lever on the pressure block, the latter may be slipped endwise from its place and thereby easily removed to permit the inspection or removal of the valve member.

Compared with the construction shown in my prior application referred to, the form of rotative valve member having two opposite recesses and admission and exhaust ports having angular relation to the cylinder port materially less than 90°, and preferably about 45°, has advantages which will appear from the following. By the use of two opposite valve recesses, the valve member makes only one-half of a revolution during each complete cycle of operations in the engine cylinder, so that it need be turned or rotated at only one-half of the speed necessary in the case of a valve member having a single valve recess, with consequent saving in friction and wear and in the amount of power required to drive the valve. Moreover, this construction affords a reduced size of the valve recesses, with consequent lessening of the valve area and valve-seat area exposed to the heat from the exhaust gases. Furthermore, by the location and arrangement of the admission and exhaust ports described, both of said ports are brought into the lower or inner half of the cylindric valve chamber, so that the pressure applied to hold the valve member against its seat serves to maintain the said valve member in close contact with the part of the valve seat surrounding said inlet and exhaust ports, as well as against the part of the valve seat in which the cylinder port is formed. The construction described, therefore, as compared with that of my prior application referred to, not only maintains uniform contact between the valve member and its seat notwithstanding the wear of the parts, but also provides for constant and uniform pressure of the valve member against the portion

of its seat containing the admission, exhaust and cylinder ports, during the operation of the valve.

Now referring to the construction shown in Figs. 8, 9, 10, 11 and 12, these figures show, in general, a valve embracing the features hereinbefore described, but containing, in addition thereto, means whereby pressure exerted on the valve through the cylinder port, and tending to lift the same from its seat, will be counter-balanced by fluid pressure exerted on an equal area of the valve member, at the side of the latter diametrically opposite said cylinder port.

10 In the form of valve shown in Figs. 8, 9 and 10, the pressure block 18 is provided, in its bearing surface diametrically opposite the cylinder port 11, with a longitudinally extending recess or channel 35^x substantially equal in length and width to the corresponding dimensions of the cylinder port. At the longitudinal center of the valve chamber, the pressure block is provided with a transversely elongated chamber 35^a with which 20 the recess 35 communicates, while in the valve seat (Fig. 10) recesses 11^a are formed, which are in communication with the cylinder port and correspond in width and length with the said chamber 35^a. A pipe or tube 36^x extends diametrically across the valve member and is so arranged as to afford communication between the cylinder port and the groove or channel 35^x. Said tube 36^x is shown as bent or curved between its ends, so 30 that its endwise expansion and contraction will not act to distort the valve member. By reason of the circumferential extension of the chamber 35^x and of the recesses 11^a, 11^a, the ends of the passage afforded by the 40 pipe 36^x serve to maintain communication between the cylinder port and the passage 35^x during substantially all of the rotative movement of the valve member, during which the power stroke of the piston is taking place and while the pressure of the expanding gases in the cylinder is being exerted upon the valve member.

The driving means for the valve member, illustrated in Figs. 8 to 10, embraces a 50 sprocket-wheel 37 (Fig. 9) mounted on an endwise cylindric extension 7^a of the valve member and held yieldingly from turning thereon by a ball 36^c and spring 36^a, which are mounted in a tube 36^d attached to the 55 valve member, said ball and spring operating as hereinbefore described.

As shown in Figs. 11 and 12, a counter-balancing fluid pressure is applied to the valve member as follows: At the side of the 60 valve casing, opposite that on which the auxiliary cylinder 19 is located, is provided a passage 38 opening at its lower end into the cylinder and connected at its upper end with a passage 39 formed in the pressure block 18, which passage communicates with

a longitudinally extending groove or channel 40 formed in the inner face of the pressure block diametrically opposite the cylinder port 11 and corresponding in area with said cylinder port. To provide a connection 70 of the passage 38 in the valve casing with the passage 39 in the pressure block, said pressure block is provided with a lateral extension 41 provided with a downwardly facing surface or shoulder which extends over 75 a corresponding upwardly facing shoulder 41^b on the valve casing. Between said shoulders 41^a and 41^b are located two elastic or compressible rings or gaskets 42 which serve to maintain a tight joint between the passages 38 and 39, while permitting the necessary shifting or yielding movement of the pressure block relative to the valve casing both sidewise and toward and from the valve seat. In this instance, the pressure block, at 80 the exhaust side of the valve, is held from rising by means of a plate 43, secured to the valve casing by a screw 43^a and extending over the projection 41 on the pressure block. A space is provided between the said plate 85 43 and the said projection, and the plate is provided, in its lower face, with a transverse groove, in which is inserted and held a cylindric rod 44 arranged parallel with the side of the pressure block and against which 90 bears the top surface of said projection. The said rod 44 forms a bearing for one side of the pressure block, on which the same may turn or rock when the opposite side of said block is swung or moved by the action of the 95 lever 23.

The advantages gained by the use of the fluid pressure counter-balancing means described, in connection with the pressure block and the means operated through the 105 pressure within the cylinder and acting on said pressure block to vary the pressure of the same against the valve member according to the pressure within the cylinder, will be understood from the following: The 110 form of device shown in Figs. 1 to 7 affords highly advantageous results when applied to explosive engines in which the variations in pressure within the cylinder are not extremely high, or, in other words, when under normal working conditions the pressure exerted by the piston 21 and transmitted therefrom to the pressure block will not be so great as to give undue pressure of the 115 valve member against its seat, or, in other words, when such a degree of pressure of the valve against its seat is not materially in excess of that required to prevent leakage of the expanding gases through the valve. When, however, the engine is designed to operate with very high pressures, the construction providing for counter-balancing of the pressure on the valve member by fluid pressure, shown in Figs. 8 to 12, is 120 of very great advantage, because thereby 125 130

all of the pressure acting on the valve member through the cylinder port is counterbalanced by the opposing pressure on the opposite side of the valve member, with the result that the pressure acting on the pressure block and holding the valve against its seat may be made practically constant and need not be in excess of that necessary to prevent leakage under maximum normal working pressure in the cylinder. In other words, in the construction providing for direct fluid counter-balancing, in connection with the pressure block and means for operating the same, the devices for giving pressure of the pressure block against the valve member may be designed, proportioned or adjusted so as to give no more than the degree of pressure of the valve member against its seat required to prevent leakage at the time of maximum pressure in the cylinder, so that most advantageous working conditions may be obtained, regardless of the degree of pressure in the cylinder at the time of the ignition and explosion of the charge therein.

With respect to the form of valve construction shown in Figs. 8 to 10, both inclusive, and in Figs. 11 and 12, the pressure transmitted from the engine cylinder to the portion of the cylindric valve member opposite the portion of the valve member which bridges the cylinder port 11 when the valve is closed, serves, in effect, to counterbalance the pressure exerted on that portion of said valve member which spans the cylinder port 11. The pressure block 18 is prevented from rising under the pressure in the cylinder by means of the piston 21 which is subjected to the same degree of pressure as the part of the valve member opposite the cylinder port. The action of the piston 21 under the pressure in the engine cylinder acts to counterbalance the upward pressure on the pressure block. Thus the valve member is subjected to just enough pressure on that side of the same opposite the cylinder port to maintain the valve member in close bearing against its seat, while the pressure on each side of the valve member is balanced. Perhaps this will be better understood by taking a concrete example. Say, for instance, that an explosion is taking place in the engine cylinder 5 and the pressure in the engine cylinder is 300 pounds to the square inch. The valve member 7 is at this time in the position it occupies when closed and that portion of said valve member which bridges the cylinder port 11 is naturally subjected to a pressure of 300 pounds to the square inch. This pressure, in the form of valve construction shown in Figs. 8 to 10 inclusive, is transmitted through the tube 36^x to the side of the valve member opposite the cylinder port 11, and the area of the valve

member at this point is equal to the area of the valve surface exposed to the pressure in the cylinder through the cylinder port 11. Thus the pressure on the side of the valve member opposite the cylinder port 11 is 70 equal to that on the opposite side of the valve member. The 300 pound pressure is also acting against the piston 21 and through this medium the pressure block 18 is held from rising or being lifted under 75 the cylinder pressure in the chamber 36^a. The action of the piston 21 counterbalances the effect of the pressure on the pressure block. The same is also true with respect to the type of valve construction shown in 80 Figs. 11 and 12. Under abnormal pressure, such as produced in the cylinder during the compression stroke of the engine piston or during the explosion in the cylinder, the piston 21 is effected and acts on the pressure block 18 to prevent rising thereof under 85 cylinder pressure. Under normal conditions, however, such as during the suction stroke of the piston or the scavenging stroke, there is no pressure in the cylinder 90 and at this time the piston 21 is not acted upon, but the spring 27 plays its part and exerts enough of a pressure on the pressure block 18 to cause the same to maintain the valve member 7 in close bearing with its 95 seat. Naturally, the spring 27 in all of the forms of valve construction shown in the drawings acts the same in each case. In this connection, it may be stated that the spring 27, arranged as described, performs the 100 same function in all of the forms of valve illustrated, inasmuch as said spring is designed to act at all times to give such excess of pressure on the pressure block as to maintain the valve member in such close bearing 105 against its seat as to insure the proper operation of the valve.

The several features of my invention may be embodied in valves materially different in details of construction from those illustrated and I do not, therefore, desire to be limited to the specific features illustrated and hereinbefore described, except as pointed out in the appended claims.

I claim as my invention:

1. The combination with a cylinder, of a valve casing provided with a cylindric valve chamber having a cylinder port and inlet and exhaust ports located at opposite sides of the cylinder port, a rotative valve member provided with two oppositely arranged valve recesses, a pressure block located between the inlet and exhaust ports and provided with a concave bearing surface in contact with the valve member, a movable member subject to the pressure within the cylinder, and power transmitting means interposed between said movable member and said pressure block and acting on said block in a direction to oppose the pressure tending to lift 115

the valve member from its seat; said cylinder port and inlet and exhaust ports being located entirely within one-half of the circumference of the cylindric bearing surface of the valve chamber.

2. The combination with a cylinder, of a valve casing provided with a valve seat and a cylinder port in said seat, a movable valve member coacting with said port, a pressure block acting on the side of the valve member opposite said seat, an auxiliary cylinder in open communication with the cylinder, a piston in said auxiliary cylinder subject to the pressure within the cylinder, pressure transmitting means embracing a spring interposed between said piston and said pressure block and acting on said block in a direction to oppose the pressure tending to lift the valve member from its seat.

3. The combination with a cylinder, of a valve casing provided with a valve seat and with a cylinder port, a valve member coacting with said port, a pressure block in contact with the side of the valve member opposite said seat, an auxiliary cylinder in open communication with the said cylinder, a piston in said auxiliary cylinder provided with a piston rod, a movable member acting to transmit pressure from said piston rod to said pressure block, in a direction to oppose the pressure tending to lift the valve member from its seat embracing a lever, and a spring applied to act on the piston rod in a direction to effect pressure of the said block against the valve member.

4. The combination with a cylinder, of a valve casing provided with a concave valve seat and with a cylinder port, and having an opening extending longitudinally of the valve seat, a rotative, cylindric, valve member, a pressure block located in said opening in the valve casing and having a concave bearing surface for contact with the valve member, said pressure block being adapted for lateral shifting movement relatively to the valve casing, means on the valve casing engaging one side of the pressure block, to hold the same positively from outward movement, and means operated by the pressure within the cylinder, acting on the opposite side of the pressure block to oppose the pressure tending to lift the valve from its seat.

5. The combination with a cylinder, of a valve casing provided with a concave valve seat and with a cylinder port in said seat, a rotative, cylindric valve member, a pressure block provided with a concave surface for contact with the valve member, a plate attached to the valve casing and engaging one side of the pressure block to hold the same from outward movement, and means subject to the pressure within the cylinder acting on the other side of said pressure block,

in a direction to oppose the pressure tending to lift the valve member from its seat.

6. The combination with a cylinder, of a valve casing provided with a concave valve seat and with a cylinder port in said valve seat, said valve casing being provided with an opening extending longitudinally of the valve chamber, a rotative, cylindric valve member, an elongated pressure block located in said opening, said pressure block being narrower than the opening and provided with outwardly facing shoulders at its opposite sides, a plate secured to the valve casing and engaging the shoulder on one side of the pressure block, a lever mounted on the valve casing and engaging the shoulder on the opposite side of said pressure block, a movable member subject to the pressure within the cylinder, and means for transmitting pressure from said movable member to said lever.

7. The combination with a cylinder, of a valve casing provided with a cylindric valve chamber, a cylinder port, and inlet and exhaust ports located at opposite sides of the cylinder port, and a rotative, cylindric valve member having diametrically opposed valve recesses extending longitudinally thereof, said valve casing being provided with an air inlet port and a gas exit port, separated from each other longitudinally of the valve chamber and located in position for simultaneous communication with the opposite ends of one of said valve recesses in the movement of the other of said valve recesses from the inlet port to the exhaust port.

8. The combination with a cylinder, of a valve casing provided with a cylindric valve chamber having a cylinder port and inlet and exhaust ports located at opposite sides of said cylinder port, a rotative, cylindric valve member provided with a longitudinally extending valve recess, a pressure block provided with a concave bearing surface in contact with said valve member, and in said bearing surface with an air inlet and a gas exit port; said air inlet and gas exit ports being adapted for simultaneous communication with opposite ends of the valve recess.

9. The combination with a cylinder, of a valve casing provided with a cylindric valve chamber, with a cylinder port, and with inlet and exhaust ports located at opposite sides of the cylinder port, a rotative, cylindric valve member having a valve recess extending longitudinally of the valve member, said valve casing being provided between the inlet and exhaust ports with an air inlet port and a gas exit port, said air inlet and gas exit ports being located in position for simultaneous communication with the opposite ends of said valve recess,

and said valve casing having an exit passage in communication with the said gas exit port.

10. The combination with a cylinder, of a valve casing provided with a cylindric valve chamber, with a cylinder port, and with inlet and exhaust ports located at opposite sides of said cylinder port, a rotative, cylindric valve member provided with a longitudinally extending valve recess, an elongated pressure block provided with a concave bearing surface in contact with said valve member, and in said bearing surface with an air inlet and a gas exit port; said 5 air inlet and gas exit ports being adapted for simultaneous communication with opposite ends of the valve recess, and said valve casing being provided with an exit passage in communication with the gas exit 15 port of the pressure block.

11. The combination with a cylinder, of a valve casing provided with a cylindric valve chamber having a cylinder port and inlet and exhaust ports at opposite sides of 25 said cylinder port, a rotative, cylindric valve member provided with a longitudinally extending valve recess, an elongated pressure block provided with a concave bearing surface in contact with the said 30 valve member and having in its said bearing surface, at one end of the block, an air inlet port, and, at the opposite end of the block, a gas exit port, and a chamber with which said gas exit port communicates, and 35 which opens through the end face of the block, said valve casing being provided with an exit passage in communication with said chamber in the pressure block.

12. The combination with a cylinder, of a 40 valve provided with a valve seat having a cylinder port, a movable valve member co-acting with said valve seat, a pressure block having a bearing surface in contact with the valve member, and means operated by the 45 pressure within said cylinder, acting to press the said pressure block toward the valve member in opposition to the pressure tending to lift the same from its seat, said pressure block being provided, in its said 50 bearing surface, with a recess which is subject to counterbalancing pressure from the interior of the cylinder.

13. The combination with a cylinder, of a valve casing provided with a cylindric valve chamber having a cylinder port, a rotative, cylindric valve member, a pressure 55 block provided with a concave bearing sur-

face in contact with the valve member at the side of the latter opposite said cylinder port, and means operated by the pressure 60 within the cylinder and acting on said pressure block to oppose the pressure tending to lift the valve member from its seat, said pressure block being provided in its said bearing surface with a recess which is substantially equal in area to the area of the cylinder port and is subject to counterbalancing pressure from the interior of the cylinder. 65

14. The combination with a cylinder, of a valve provided with a valve seat having a cylinder port, a movable valve member co-acting with said valve seat, a pressure block having a bearing surface in contact with the valve member, and provided, in its said bearing surface, with a recess which is substantially equal in area to the cylinder port, and means operated by the pressure within 70 said cylinder, acting to press the said pressure block toward the valve member in opposition to the pressure tending to lift the same from its seat, the valve being provided with a passage leading from the interior of the cylinder to the said recess in the pressure block, affording a counterbalancing fluid pressure in said recess. 75

15. The combination with a cylinder, of a valve casing provided with a cylindric valve chamber having a cylinder port, a rotative, cylindric valve member, a pressure block provided with a concave bearing surface in contact with the valve member at the side of the latter opposite said cylinder port, said pressure block being provided in its said bearing surface with a recess 80 which is substantially equal in area to the area of the cylinder port, and means operated by the pressure within the cylinder and acting on said pressure block to oppose the pressure tending to lift the valve member from its seat; said valve member being provided with a transverse passage opening through its opposite sides and adapted to afford communication between the interior of the cylinder and the said recess in the pressure block. 85

In testimony, that I claim the foregoing as my invention I affix my signature in the presence of two witnesses, this 16th day of July A. D. 1913.

WILLIAM H. FAUBER.
